BOTTLE COOLER

Herman W. Kleist, Chicago, Ill., assignor to Dole
Refrigerating Machine Company, Chicago, Ill.,
a corporation of Illinois

Application August 10, 1933, Serial No. 684,499

2 Claims. (Cl. 62—141)

This invention relates to bottle cooling devices and has for its object to provide a new and improved device of this description. The invention has a further object to provide a simple, cheap and effective device for cooling beverages while in the bottles. The invention has other objects which are more particularly pointed out in the accompanying description.

Referring now to the drawing, Fig. 1 is a view of one form of device embodying the invention; Fig. 2 is a sectional view therethrough; Fig. 3 is a view showing a modified construction; Fig. 4 is an enlarged view showing the section through the cooling plate.

Like numerals refer to like parts throughout the several figures.

Referring now to the drawing, I have shown a bottle cooler which consists of a receptacle 1 made up of heat insulating material. At the bottom of the receptacle is a cooling plate 2. This cooling plate preferably extends entirely over the bottom of the receptacle so that it completely covers it and forms the upper face of the bottom, there being below it the heat insulating member 3. The plate may be arranged in any desirable manner. I prefer to provide a layer of material, such as asphalt, beneath the plate and between it and the heat insulating member, the plate being thus sealed in asphalt or other suitable material. The interior of the receptacle is preferably lined, and I prefer to use any suitable lining 4, which may be a galvanized lining if desired. The plate is preferably soldered or brazed at the edges to the lining to make a water tight receptacle. The receptacle may be made water tight in any other manner. The receptacle is provided with a door 5 through which the bottles may be inserted and removed.

When a single receptacle is used I prefer to mount it upon supports 6 so that it may be of the right height to be easily accessible. An inlet 7 may be provided for supplying water to the receptacle, said inlet having a valve 8 by means of which it is opened and closed. This inlet may be omitted if desired and the water simply poured into the receptacle. The refrigerant is circulated through the plate and the upper face of the plate makes contact with the water. This cools the water uniformly and the bottles are placed in the water with their bottoms on the top of the plate. The water is preferably of such height that the bottles will still rest on the plate and not float. The water may be omitted if desired and the bottles simply placed on the top of the cold plate.

Instead of providing a single receptacle 1, I

may have a series of receptacles or an enlarged compartment with a series of receptacles in it, as shown in Fig. 3. In this construction there are the receptacles 1 and 1a located one above the other, each arranged substantially as shown in Figs. 1 and 2 with a plate 2 sealed in asphalt and with the lining 4 of suitable material, the plates forming the bottoms of the receptacles. The receptacle 1 has the doors 2a at the top and the receptacle 1a has the doors 3a at the side. In Figs. 2 and 3, I have indicated the height of the water at 9 and have indicated also some bottles 10 in position.

The plate 2 is preferably a vacuum plate which consists of two separated sheets of metal 11 and 12 with a coiled pipe 13 between them, the air being exhausted from between the sheets so as to form a vacuum therein so that the pressure of the outside air presses the sheets tightly against the pipe so as to insure a strong pressure contact between the pipe and the sheets 11 and 12. The air is drawn out from between the sheets by connecting a pump with the pipe 14 which, after the air is withdrawn, is shut off by means of the valve 15. The refrigerant is circulated through the pipe 13, entering and leaving by the pipes 16 and 17. I have found that by means of a device of this kind, and particularly with the vacuum plate, an exceedingly efficient bottle cooler can be made at very low cost.

By having the water directly in contact with the plate it cools quickly and is kept in the proper temperature, and the cooling of the beverage in the bottles is effected both by the water and directly by the plate, the bottles resting thereon. I have found that the direct contact of the water with the plate greatly increases the efficiency of the device and insures a quick cooling of the beverage in the bottles and the maintaining of the beverage at the proper temperature. By having the bottles also rest on the plate the efficiency is increased.

I claim:

1. A bottle cooler comprising a heat insulated receptacle, a cooling plate extending across said receptacle so as to form the bottom thereof, said cooling plate comprising two separated metal sheets, a pipe through which the refrigerant is circulated between said sheets, the sheets being hermetically sealed and the air being withdrawn, the sheets being tightly pressed against the pipe by the pressure of the outside air, and bottles resting on the cooling plate.

2. A bottle cooler comprising a heat insulated receptacle, a cooling plate extending across said

receptacle so as to form the bottom thereof, said cooling plate comprising two separated metal sheets, a pipe through which the refrigerant is circulated between said sheets, the sheets being hermetically sealed and the air being withdrawn, the sheets being tightly pressed against the pipe

by the pressure of the outside air, bottles resting on the cooling plate, the receptacle being partially filled with water in contact with the cooling plate and with the bottles resting thereon.
